EXPANDING POWER MEANS

Lawrence M. Persons, St. Louis, Mo., assignor,
by mesne assignments, to Automatic Control
Corporation, St. Louis, Mo., a corporation of
Delaware

Application July 16, 1936, Serial No. 90,955

3 Claims. (Cl. 297—3)

The present invention relates generally to expanding power means, and more specifically to a multiple diaphragm which is actuated by a thermally-sensitive solid charge.

Heretofore, various types of expanding power means have been devised, including diaphragms and bellows. For certain purposes, expanding power means of the conventional bellows type have been found to be unsatisfactory in view of the fact that a positive transmission of power cannot be achieved.

An object of the present invention is to provide an expanding power means of the diaphragm type which incorporates the multiple expanding features of the bellows type.

Another object is to provide a diaphragm which is positive in its transmission of power.

Another object is to provide a diaphragm which includes a plurality of superposed folds adapted to multiply by that number the effective movement which is produced by a single fold.

Another object is to provide a diaphragm which is cheap, easy to manufacture, and thoroughly efficient and satisfactory in operation.

Other objects and advantages of the invention will appear from the following description, taken in conjunction with the accompanying drawing, in which—

Fig. 1 is a side elevation of a multiple diaphragm and an associated tube and bulb, constructed in line with the present invention, shown with an associated actuated mechanism.

Fig. 2 is a plan view of the embodiment shown in Fig. 1, the actuated mechanism being omitted.

Fig. 3 is a central section showing a multiple diaphragm connected directly to an associated bulb.

Fig. 4 is a section on the line 4—4 of Fig. 3.

Referring to the drawing by reference numerals, 10 indicates generally a multiple diaphragm constructed according to the present invention. In Figs. 1 and 2, the diaphragm 10 is shown as the extension of a tube 11 which leads from a bulb 12. In Fig. 3, the diaphragm 10 is disclosed as directly leading from the bulb 12, there being no intermediate tubing 11 as in Figs. 1 and 2. Whether or not intermediate tubing is employed will, of course, depend upon the use and installation of the diaphragm. It will, of course, be understood that the bulb 12 contains a thermally-sensitive fluid which communicates with the diaphragm in operative relation, as will be more particularly described below.

In the present disclosure, the diaphragm 10 comprises a portion of tubing which is flattened

and which is redoubled or folded upon itself as at 13 and 14 to provide a plurality of superposed segments 15. The segments so produced include opposed walls 16 connected by the rounded ends 17. The flattened portion of tubing contains a co-extensive filler strip 20 which is of a rectangular cross section having the sides 21 and ends 22 and its adjacent rounded end 11. The filler strip 20 is, of course, inserted into the flattened tubing prior to the bending or folding operation, and is held in position by sealing the end of the tubing against and around the filler strip, as at 24. There is a very small space between the flat sides 21 of the filler strip 20 and the opposed walls 16 of the tubing, so that fluid may be forced into a position to expand the tubing. In Figs. 3 and 4, this space between the flat sides 21 of the filler strip and the opposed walls of 15 the tubing has been exaggerated to better illustrate the device.

The flattened tubing may be doubled upon itself any number of times to provide any desired diaphragm expansion. There is no actual space between the doubled back segments of the tubing, as is shown in the figures, but the metal will 25 abut or rest in contiguous relation, as is shown in Fig. 1. This space is provided in Figs. 3 and 4 for the purpose of clarity of illustration.

The filler strip is used in the flattened tubing for the purpose of reducing the space available 30 for thermally-sensitive fluid, and to provide a means by which the tubing can be folded without producing angled bends and without breaking at the ends. Without the use of the filler strip, there would also be present the possibility of 35 completely closing the diaphragm during the flattening operation which would prevent the ingress of fluid. Relative to reducing the space made available for the fluid, were there as much liquid in the diaphragm and the tube leading 40 thereinto as in the bulb, then the bulb would lose its effectiveness and purpose, for the diaphragm would expand to actuate associated mechanism upon heat being applied thereto and to its tube. This would defeat the purpose of 45 the device, for the diaphragm for successful use is adapted to be actuated primarily by the expansion of the liquid within the bulb, which is disposed at the point of temperature control, or at a point whose temperature is employed to 50 control mechanisms and temperatures. By rendering the fluid in the diaphragm and tube negligible, substantially the full expansion of the diaphragm is effected through the expansion of the liquid in the bulb.

In Fig. 1, there is shown diagrammatically one type of mechanism adapted to be actuated by the diaphragm. A stud 25 is welded or otherwise fixed to the diaphragm. A lever 26 is pivoted at 27 to a support and carries at one end a contact 28 adapted to cooperate with an associated contact 29 which is fixed to a support 30. A spring 31 serves to bias the lever 26 toward a position in which the contacts 28 and 29 are open. It is thus apparent that, upon expansion of the diaphragm, the stud 25 will, at a predetermined point in this movement, strike the lever 26 to pivot it around the point 27 to close the contacts 28 and 29. Obviously, this is only one type of mechanism adapted to be actuated by the diaphragm, the invention contemplating as within its scope various types of actuated mechanisms controlled by an expanding power means.

20 *Operation*

The diaphragm of the present invention functions in its expanding movement to multiply the movement obtained in a single segment. When the bulb 12 is subjected to heat, the thermally-sensitive fluid therein expands. Inasmuch as the weakest portion of the assemblage is the diaphragm itself, the liquid, in its effort to escape from the tube as a result of the expansion, will cause the flattened sides of the diaphragm to bulge or expand. Each segment of the diaphragm will be equally expanded so that the movement obtained will be the sum of the expansions of the segments. The flattened external surfaces of the segments are in abutting relation and, therefore, the movement obtained through expansion of the fluid will be positive. It will be understood that the above description and the accompanying drawing have been given by way of illustration and example and

not as limitation, the invention being limited only by the following claims.

What is claimed is:

1. In a device of the kind described, a diaphragm comprising a section of tubing flattened and folded so that the folds contact throughout the full area of the flattened sides when collapsed, a thermally-sensitive fluid in the tubing, and a filler strip in said tubing to restrict the fluid space. 5

2. In a device of the kind described, a bulb, thermally-sensitive fluid in said bulb, a diaphragm operatively connected to said bulb comprising a section of tubing, said section of tubing being flattened and folded to provide superposed segments contacting throughout the full areas of the opposed flat sides when the diaphragm is in collapsed relation, and a filler strip in and coextensive with said diaphragm to reduce the fluid space. 10

3. In a device of the kind described, a bulb, thermally-sensitive fluid in said bulb, a diaphragm comprising a flattened piece of tubing, said tubing being folded to bring the folds produced into superposed relation contacting throughout the full areas of the opposed flat sides when collapsed, said opposed flat sides contacting throughout substantially the full areas thereof when expanded, said diaphragm being connected to said bulb at one end whereby said diaphragm 20 forms a continuation of said bulb, fluid in said diaphragm communicating with said fluid in said bulb, and a filler strip coextensive with said diaphragm of a cross-section restricting the fluid space within the diaphragm when in 25 normal position to a small channel at each side of said strip whose cross-section is semi-circular, the radius of which is equal to substantially half the thickness of said filler strip. 30
